DISK DIAMOND DRESSING TOOL

Charles J. Koebel, Grosse Pointe, Mich., assignor
to Koebel Diamond Tool Company, Detroit,
Mich., a corporation of Michigan

Application April 19, 1943, Serial No. 483,576

6 Claims. (Cl. 125—39)

The present invention relates to a new and improved construction of a diamond dressing tool of the type employed for the dressing and truing of grinding wheels. Due to the almost universal adoption of grinding wheels for the finishing of machine and motor parts of all types to bring the parts to the desired finished sizes within the very precise limits required in present day manufacturing methods, and particularly in mass production manufacturing, there has been a consequent increased and wide-spread use of diamond dressing tools for truing the grinding wheels and also for keeping the working faces thereof in the most effective operating condition.

It has been previously found that the diamond dressing tool should preferably not be presented radially against the surface of the grinding wheel and definitely not at an angle to the radius against the direction of wheel travel but that such tools will function most efficiently at a drag angle varying from 3 to 15 degrees. The expression drag angle is understood in the art to be that angle formed between the axis of the tool and the radius of the grinding wheel through the point of contact between diamond and wheel with the axis of the tool extending towards the direction of wheel travel.

It is also previously known in the art that when a diamond dressing tool has been used to dress a grinding wheel several times there is a tendency for the diamond or diamonds in the tool to wear flat so that the diamonds no longer dress the wheel efficiently. It has therefore been the practice to turn the diamond dressing tools at intervals, whereby new sharp edges of the diamonds are presented against the face of the grinding wheel, the tool being directed at a certain drag angle against the wheel, or to change the amount of the drag angle, thereby achieving the same effect.

It has also previously been found that for many types of dressing, a diamond dressing tool set with two or several diamonds in the front surface of the tool touching the grinding wheel simultaneously, effect a better dressing or truing than a tool set with one single diamond. The multiple type tool is set with diamonds of relatively small size of from say .01 to .50 carat, each arranged in spaced, or properly arranged relationship in the face of the tool. These multiple type tools possess the further advantage of being less costly than the large stones required for tools set with single diamonds which are scarce and expensive. It is also possible with the multiple type tools either to turn them in the tool holder

from time to time or to change the drag angle so as to present new sharp edges of the diamonds to the grinding wheel to perform a better dressing operation as above described.

The use of grinding wheels for forming grinding, i. e. for the production of work pieces which depart from straight cylindrical form has become more prevalent in recent years. Certain classes of form grinding, and more particularly what is known as step grinding, make it necessary to employ either a diamond dressing tool having but a single diamond or a multiple diamond type of tool in which the diamonds are located in one line across the face of the wheel and so that the diamonds may be presented to the face of the grinding wheel in a plane transverse to the axis of the wheel.

When a multiple type tool is used for step grinding, namely, a tool with two or more diamonds in a single row and placed transverse to the axis of the grinding wheel, it is evident that the drag angle cannot be changed and the tool cannot be turned in the holder in order to present new sharp edges of the diamonds against the wheel. Consequently when the diamonds have been worn flat or dull, it has heretofore been necessary, in order to prolong the life of the tool, to re-set the diamonds, which is a rather costly procedure.

The present invention has for its principal object to provide a new and improved tool particularly adapted for dressing grinding wheels employed for step grinding which tool is so constructed and arranged and set with a plurality of diamonds that although the tool may be presented against the wheel with the diamonds arranged in a plane transverse to the axis of the grinding wheel, the tool may be turned without removing the same from the holder for the purpose of presenting first, new diamonds consecutively against the tool and later, new sharp edges of the diamonds that have been partially used and worn.

It is also a further object to provide a new and improved construction of a diamond dressing tool of the character set forth in which it is possible to wear the diamonds out substantially completely without the necessity for re-setting them.

Another object of the invention is to provide a diamond dressing tool with a much larger number of diamonds therein than heretofore employed and which may be consecutively brought to operating position to present new cutting edges against the grinding wheel.

A further object of the invention is to provide

a new and improved type of diamond dressing tool provided with a plurality of relatively small diamonds carried in a member that is movable with respect to the shank of the tool so that such movable member may be quickly and readily moved or turned from time to time to present new diamonds consecutively to the face of the wheel without disturbing the setting of the shank of the diamond dressing tool in the tool holder of the grinding machine.

The above and other objects of the present invention will be understood more fully from the following more detailed description and by reference to the accompanying drawing forming a part hereof wherein

Fig. 1 is a plan view showing a tool of the present invention in position for dressing a stepped grinding wheel.

Fig. 2 is a view in side elevation with the grinding wheel broken away to show only a fragmentary part thereof.

Fig. 3 is an enlarged somewhat diagrammatic view in side elevation of the dressing tool of the present invention to illustrate the manner in which the diamonds thereof may be successively presented to the dressing tool to be dressed.

It is of the utmost importance in the use of diamond dressing tools that the tool be presented to the wheel at the proper angle. It is found in actual practice that unless a diamond dressing tool is positioned at an angle to the surface of the wheel being dressed that there is a great tendency for the tool to gouge into the wheel. When this occurs the grinding face of the wheel is not only marred so that considerable additional dressing thereof is required to put it into proper working condition, but when a diamond dressing tool gouges into the wheel, the reaction forces are such that a heavy strain is placed upon the diamond which tends either to break the diamond or to dislodge it entirely from the tool shank. When the diamonds are dislodged from the tool shank they frequently may be thrown a considerable distance so that they are frequently irreversibly lost, and as the diamonds are quite expensive, it is highly important that gouging of the tool into the wheel be obviated as far as possible. It has been found in practice that a drag angle varying from 3 to 15 degrees, in accordance with circumstances, gives the most satisfactory results. The showing of Fig. 2 in the drawing wherein the arrow indicates the direction of rotation of the wheel 11 and wherein the tool 20 is inclined downwardly from a line normal to the circumference of the wheel at the point of contact of the tool with the wheel illustrates the drag angle referred to.

The type of grinding known as form grinding or step grinding and wherein the grinding wheel is dressed to a pre-determined contour to correspond to the finished contour of a workpiece to be fabricated presents different problems with respect to the dressing of the grinding wheel than are encountered when a grinding wheel having a straight cylindrical contour is employed. As the tool of the present invention is particularly adapted for the dressing of grinding wheels for either form or step grinding, as well as for ordinary straight cylindrical grinding wheels, the tool has been shown in the drawing in connection with a step grinding wheel. As shown in Fig. 1, the grinding wheel 11 is indicated as being provided with three cylindrical grinding surfaces 11-a, 11-b and 11-c of different diameter which results in the formation on the wheel of the steps or

shoulders 11-d and 11-e. Because of the presence of these steps or shoulders 11-d and 11-e on the wheel it is necessary in step grinding to employ either a single point tool or, if a multiple tool is employed, to have the diamonds arranged in a single row lying in a plane transverse to the axis of the wheel so that the diamond points on the tool may enter into, and properly form, the contour of the shoulders 11-d and 11-e.

The tool of the present invention consists of a tool shank 20 provided with a yoke 21 consisting of the spaced jaws 22, 23. The jaw 23 is provided with a threaded hole for the reception of the threaded end of a cap screw 24, the jaw 22 having a through, or unthreaded hole, for said screw. Mounted on the screw 24 and within the space between the jaws 22, 23 is the diamond dressing tool 25 of the present invention. The tool 25 is in the form of a narrow wheel, or flat cylindrical disk having a plurality of diamonds 26 embedded in the material of the disk 25 and projecting from the periphery thereof. The disk 25 is preferably constructed of sintered material consisting of a mixture of powdered metals, such as described in the co-pending patent application of Lindqvist-Martin, Serial No. 435,702. The diamonds 26 are suitably arranged in equally spaced relationship around the periphery of the disk, when the metals are in powdered form after which the metal powder is sintered and pressed simultaneously into a compact, coherent and rigid form with the diamonds firmly embedded therein and secured to the disk so that they project radially from the periphery thereof to substantially the same extent and along substantially in the same circumferential line. The present invention however is not limited to the setting method described above, as the diamonds may be secured to the disk by other sintering methods or by casting, brazing or peening the diamonds into a suitable metal disk.

One side face of the disk 25 preferably has formed therein either during the pressing and sintering operation, or by any other suitable method, a plurality of grooves 27, or drill spotted depressions, there being the same number of grooves in the side face of the wheel as there are diamonds in the periphery thereof. The grooves 27 are intended to function as locating means to insure that the wheel will be held in proper position relative to the diamonds provided in the face of the wheel and for this purpose suitable means such, for example, as the screw 28 is provided in the jaw 23 of the yoke 21, the inner end of the screw 28 having a reduced tip 29 adapted to engage within the grooves 27.

The manner in which the dressing tool is employed is as follows:

The disk 25 being mounted within the yoke 21 is adjusted to bring one of the grooves 27 in alignment with the pointed tip 29 of the screw 28 after which the screw 24 is tightened to secure the disk rigidly between the jaws 22, 23 of the yoke, the clamping action of the inner faces of the jaws 22, 23 against the side faces of the disk and the engagement of the pointed end 29 of the screw 28 with the groove 27, holding the disk securely against rotation. The grooves 27 are positioned relatively to the diamonds 26 so that when the tool is presented to the grinding wheel 11 at the proper drag angle, as illustrated in Fig. 2, two diamonds simultaneously attack, or engage the face of the wheel. When, after a certain period of use, the diamonds have been worn flat, or dull, the screw 24 is loosened and the disk 25 is turned

to bring into engagement with the pointed end 29 of the screw 28 the groove 27 which is spaced two grooves from the one with which the screw 28 formerly was engaged.

The manner in which the diamonds are successively brought into engagement with the grinding wheel can perhaps best be understood by reference to the enlarged view Fig. 3 of the drawing wherein the grinding wheel 11 and the diamond dressing tool are respectively illustrated by the numerals 11 and 25, the points A, B represent the location of two of the diamonds of the tool 25 which may be assumed to have been originally employed at the beginning of use of the tool. After the two diamonds located at points A and B have been worn to such an extent that they no longer work effectively, the screw 24 is loosened and the wheel 25 rotated through $\frac{1}{16}$ of a revolution (assuming that the wheel is originally provided with 32 diamonds) or the equivalent of two grooves 27; this will bring the diamonds at the points indicated at C and D into operative position to engage the face of the grinding wheel 11. This operation is repeated in equal increments around the face of the disk until the diamonds located at the points E and F have been used, after which the tool, or disk, 25 will then be rotated only through $\frac{1}{32}$ of a revolution which will bring the diamonds located at the points E and A into operative position, thus presenting them to the face of the grinding wheel at a different angle from that in which they were formerly used. After the diamonds at E and A have been again worn down in their new position of use, the wheel is next again rotated through $\frac{1}{16}$ of a revolution as before, or the equivalent of two grooves 27 to bring the diamonds B and C in operative position to engage the face of the grinding wheel. After the diamonds B and C have been worn down in their new positions of use the wheel is again rotated each time for a resetting through $\frac{1}{16}$ of a revolution, thus causing each and every one of the diamonds on the periphery of the wheel to be re-presented to the tool at a different angle. After the disk 25 has been rotated through a complete 360 degrees of angular rotation back to the point where the diamonds E and A are again presented, the tool is then moved to bring the diamonds A and B again into positions to engage the face of the grinding wheel that was occupied by them in the first use of the tool.

Due to the fact that the diamonds A and B in the second use of the tool were presented to the wheel in different relative positions than that in which they stood in their first use, the faces of these two diamonds would be worn to such an angle that they will again present new sharp and effective cutting edges of the tool when re-set back to their original positions.

It will be understood that the present tool is firmly held against rotation when used to perform a wheel dressing operation and that due to the circular or cylindrical outer periphery of the tool, and the re-setting movement of it through the small amounts of angular rotation results in presenting the diamonds which engage the wheel to the wheel at a different drag angle after each re-setting than that at which they were presented at the former setting. It will therefore be understood that the present tool, and the manner in which it is to be used, is to be distinguished from the use of a plurality of small diamonds mounted within the face of a disk which is mounted for rotation in a tool holder and which is permitted to rotate when the diamonds in the

face of the tool are pressed against the periphery of the grinding wheel.

Having thus described my invention what I desire to secure by Letters Patent is:

1. A diamond dressing tool comprising a narrow cylindrical disk carrying a number of small diamonds arranged in substantially equally spaced relationship around, and projecting partially from, the periphery of said disk, and means for holding said disk against rotation in adjusted position for dressing a grinding wheel and so as to present more than one diamond contact simultaneously to said wheel, the spacing of said holding means relative to the spacing of said diamonds being such that upon subsequent settings of said disk to re-present any one of said diamonds to said wheel it will be in a different angular position than in its immediately preceding operable setting.

2. A diamond tool for dressing a grinding wheel comprising a tool shank having at one end thereof of opposed clamping means, a flat cylindrical shaped disk carried by said clamping means, a plurality of small diamonds arranged in substantially equally spaced relationship around, and projecting partially from, the periphery of said disk, means for tightening said clamping means against the side faces of said disk to hold the same against rotation during a wheel dressing operation, said disk and said clamping means being provided with inter-engaging locking means to serve to locate said disk with at least a pair of said diamonds in proper pre-determined relationship to engage the face of the wheel to be dressed and to hold said disk against rotation during the dressing operation, and said inter-engaging means being so arranged relatively to the spacing of said diamonds that the members of each pair of diamonds which engage the wheel on each setting will be different, after each complete rotation of said disk, from those which engaged the wheel in each setting of said disk during such rotation.

3. A diamond tool for dressing a grinding wheel comprising a tool shank having at one end thereof of a yoke consisting of a pair of clamping jaws, a flat cylindrical shaped disk mounted between said clamping jaws, a plurality of small diamonds arranged in a single row in equally spaced relationship around, and projecting from, the face of said disk, at least one of the side faces of said disk and at least one of said jaws, being provided with cooperating, inter-engaging locking means to serve to bring at least a pair of said diamonds simultaneously into operative relationship with the face of the wheel to be dressed and means for clamping said jaws against the side faces of said disk and to hold said inter-locking means in engagement to prevent rotation of said disk during a wheel dressing operation, and said inter-engaging means being so arranged relatively to the spacing of said diamonds that the members of each pair of diamonds which engage the wheel on each setting will be different, after each complete rotation of said disk, from those which engage the wheel in each setting of said disk during such rotation.

4. A diamond tool for dressing a grinding wheel comprising a tool shank, a flat cylindrical shaped disk carried thereby, a plurality of small diamonds arranged substantially in a cylindrical plane in substantially equally spaced relationship around, and projecting partially from, the periphery of said disk, said disk and clamping means each be-

ing provided with inter-engaging indexing means arranged in definite pre-determined relationship with respect to said diamonds so as to locate the members of a pair of adjacent diamonds substantially in equally spaced relationship on each side of the plane passing through the center of said disk and the center of the grinding wheel to be dressed with said pair of diamonds in contacting operative engagement with the periphery of said grinding wheel, and said inter-engaging means being so arranged relatively to the spacing of said diamonds that the members of each pair of diamonds which engage the wheel on each setting will be different, after each complete rotation of said disk, from those which engaged the wheel in each setting of said disk during such rotation.

5. A diamond tool for dressing a grinding wheel comprising a tool shank, a flat cylindrical shaped disk carried thereby, a plurality of small diamonds arranged substantially in a cylindrical plane in substantially equally spaced relationship around, and projecting partially from, the periphery of said disk, said disk and clamping means each being provided with inter-engaging indexing means arranged in definite pre-determined relationship with respect to said diamonds so as to locate the members of a pair of adjacent diamonds substantially in equally spaced relationship on each side of the plane passing through the center of said disk and the center of the grinding wheel to be dressed with said pair of diamonds in contacting operative engagement with the periphery of said grinding wheel, and means for tightening said clamping means to hold said disk in indexed position, and said inter-engaging means being so arranged relatively to the spacing of said diamonds that the members

10 of each pair of diamonds which engage the wheel on each setting will be different, after each complete rotation of said disk, from those which engaged the wheel in each setting of said disk during such rotation.

6. A diamond tool for dressing a grinding wheel comprising a tool shank, a flat cylindrical shaped disk carried thereby, a plurality of small diamonds arranged substantially in a cylindrical plane in substantially equally spaced relationship around, and projecting partially from, the periphery of said disk, inter-engaging indexing means carried by said disk and said tool shank, the inter-engaging means on said disk being arranged in definite pre-determined equally spaced relationship to provide an index point corresponding to each of the diamonds carried by the periphery of said disk and cooperating with the inter-engaging means of said tool shank to locate the members of an adjacent pair of diamonds in substantially equally spaced relationship on each side of a plane passing through the center of said disk and the center of said grinding wheel, and means for tightening said clamping disk to hold the members of an adjacent pair of diamonds simultaneously in contact with the periphery of the grinding wheel and against rotation during a wheel dressing operation, and said inter-engaging means being so arranged relatively to the spacing of said diamonds that the members of each pair of diamonds which engage the wheel on each setting will be different, after each complete rotation of said disk, from those which engaged the wheel in each setting of said disk during such rotation.

35 CHARLES J. KOEBEL.
